ABSTRACT: According to the invention the vast hulls of cargo carrying ships (freighters) are not obstructed by any permanent installations of structure to receive the cargo which may and often does vary in return voyages as compared with the character of outgoing cargo and hence the difference in return cargo often dictates a difference in adaptations of internal structure to receive and best retain (from shifting) such return cargo.

SHIPBOARD CARGO STOWAGE CONSTRUCTION

The present invention relates to shipboard cargo stowage construction.

An object of the invention is to provide knockdown elongated support members, in sufficient numbers or supply, for temporary erection in the cargo hold of a vessel of freight classification to provide one or a number of hatchways or divisions of the hold, which elongated members act as guideways and supports for 'tween decks, containers, pallets or the like receivers of cargo to the end that such 'tween decks, for example, may be supported individually from the elongated members whereby the decks and their individual loads will not devolve upon under cargo loads on under decks with disastrous consequences to such under loads and their decks.

Another object of the invention is to provide knockdown members which may be temporarily and quickly erected in large normally vacant spaces in the cargo holds of ships whereby the vacant spaces may be quickly converted into a number of cargo receiving holds of varying capacities and sizes for the quick stowage of cargos of various kinds and sizes.

A further object of the invention is to provide in knockdown condition groups of members which may be erected quickly in relation to other similar groups to form cells for reception of containerized or other cargo in which the groups are adjustably connected together by means which may be quickly adjusted to alter the relative positions of said groups whereby the latter may be accurately finally positioned to receive a variety of different sizes of cargo or containers, which will conserve space and are of such construction as to be quickly erected, adjusted and finally dismantled.

With the foregoing and other objects in view the present invention will be more fully described hereinafter, and will be more particularly pointed out in the claims appended hereto.

In the drawings, wherein like symbols refer to like or corresponding parts throughout the several views:

FIG. 1 is a perspective view of a form of basic element, being an elongated vertical member adapted, in concert with other like members, to form individual separate hatchways or cells for receiving cargo on decks, in containers or otherwise.

FIG. 2 is a fragmentary perspective view of a portion of the hold of a cargo vessel in which selected groupings of the angle iron basic vertical members are shown as examples of temporary cargo cell arrangements.

FIG. 3 is a perspective view of a corner standard comprised of four of the vertical angle iron members in an arrangement in which the vertical angle iron members serve as a corner post for four separate cargo cells completed by three additional corner standards as shown in FIG. 11.

FIG. 4 is a top plan view of the corner standard showing portions of four cargo containers supported in the standard.

FIG. 5 is a fragmentary side elevational view of the corner standard with connecting devices.

FIG. 6 is a perspective view with parts broken away of a form of connecting device for the angle iron members.

FIG. 7 is a fragmentary horizontal sectional view taken through the hull showing hinged or pivoted gates for converting cells to accommodate 20 or 40 foot cargo containers.

FIG. 8 is a perspective view showing the gates carrying vertical angle iron members in place crosswise of the hull forming 20 foot cells with cargo containers in place in one of the cells.

Referring more particularly to the drawings, in FIG. 2, 10 designates the bottom shell of a boat hull, 11 the tank top and 12 the intermediate bottom tank.

Referring more particularly to FIG. 1 in which a representative form of knockdown vertical supporting member is shown, such member cross-sectionally considered is preferably of angle iron form comprising the webs or flanges 60, 61 related in a preferably right-angle connection. The height of these vertical members will vary with the depth of the hold or the depth of cell to be staked out. The vertical members may rest 75

on the tank top 11 or on any 'tween deck and are advantageously of metal. In one of the flanges may be made slots 62 for receiving movable bolts or support members carried by the pallets.

5 In the detached condition of FIG. 1 these knockdown vertical support members 60, 61 may be stowed in any suitable numbers in any part of the hold or elsewhere and are well adapted to be set up on end at short notice in assemblies of four as shown at D, E, F, and G in FIG. 2 or A, B, C, and D in FIG. 8, to thereby delimit and constitute, a cell or hatchway suitable for receiving 20 or 40 foot pallets or containers of cargo of any prescribed sizes.

10 The support members may be made of iron, steel or other appropriate material and may be welded or otherwise attached to longitudinal and transverse bulkheads or other supports. At intermediate areas which lack bulkheads the support members may be assembled in groups of four in number, for instance in a relationship as indicated at D, E, F and G in FIGS. 2, 3 and 4, in which the assemblages constitutes corner standards serving four separate cargo cells.

15 Referring more particularly to FIGS. 3, 4 and 5 inclusive, the angle iron assemblages or corner standards D, E, F and G are preferably connected at various elevations by connector members 63 of preferably a cruciform construction having radiating arms 64, 65, 66 and 67. The connections may be by welding to leave the right-angle surfaces of the angle irons smooth for the free sliding up and down therein of the corner portions of the pallets or containers. The arms of the connector members 63 are preferably hollow as shown and open

20 through outer ends thereof. In the arms 64 and 66 are aligning slots 68 and 69 which register with the slots 62 in the webs or flanges 61 of the vertical corner members D, E, F, and G so as to permit the movable support bolts 27 to be projected therethrough to assume the support of the 'tween decks or the container pallets when finally in place.

25 The arms 65, 67 are open-ended and have aligned bolt holes 70 for removably receiving headed bolts 71 which pass through perforated forked clips 72 and the interleaved connector strips 73. Rods or cables 74 join clips 72 of next-in-line corner standards as shown in FIG. 11. These rods or cables 74 preferably include turnbuckles 75 for adjusting accurately the distance between adjacent corner standards.

30 Referring more particularly to FIGS. 7 and 8, gates 76 and 77 are pivoted vertically at outer ends in opposite longitudinal bulkheads 78 and 79 to swing out and meet at their free ends to provide a cross partition dividing 40 foot long hatchways into two 20 foot hatchways so as to accommodate either 40 foot long or 20 foot long containers or pallets.

35 In FIG. 7 the gate 76 at its pivoted end carries two vertical support members identified at 80 and 81, at its free end two other vertical support members 82 and 83 and at its intermediate portion four vertical support members 84, 85, 86 and 87.

40 Similarly the gate 77 carries two outer vertical support members 88, 89, four intermediate support members 90, 91, 92 and 93 and two inner support members 94, 95.

45 When the two gates move to the transverse dotted line positions, their various vertical support members will align with the permanent end support members 96 and 97 of the 40 foot cells or hatchways and thus convert the four 40 foot hatchways to eight 20 foot cells.

50 FIG. 8 shows a very similar arrangement with the additional of the turnbuckles 75 and the rods or cables 74.

55 I claim:

1. For use with a cargo vessel having a cargo hold, a. elongated knockdown members removably introducable into the hold and adapted to be detachably assembled and erected in the hold in spaced relation to one another and in selected geometric patterns circumscribing the whole area of the hold or selected divisions of the whole area thereof until the whole area or selected segments only of the whole area are spaced off and delimited by coordinate assemblies of the knockdown elongated members,

- b. cargo containing members of similar geometric patterns slideable up and down within the confines of the assembly or assemblies of said elongated members and being guided in up and down movements by said assembled elongated members, in which groups of at least four said elongated members are associated,
  - c. cruciform means connecting the members of each group, and
  - d. adjustable means connecting the cruciform means of adjacent groups, said adjustable means comprising
  - e. perforated connector strips passing through the cruciform means;
  - f. forked perforated clips fitting over the end portions of the connector strips, and
  - g. bolts removably fitting through the perforations of the strips and clips and perforations of the cruciform means.
2. In a cargo ship having a smooth decking enclosed by bulkheads,
- a. stationary vertical guide members secured to the bulkheads at spaced locations to define sides of cargo holds,
  - b. groups of other movable guide members slidably resting at their lower ends on the smooth decking and adapted when properly aligned to mate with selected bulkheads guide members and other movable guide members to together complete a plurality of upright guideways for cargo containers,
  - c. means for individually connecting groups of slideable guide members, and

- d. adjustable means included in said connecting means to cause nice relative adjustments of the groups by sliding the grouped guide members along the smooth decking into completely accurate registration with other stationary and/or movable group guide members.
3. The combination of claim 2, further comprising
- e. hollow central members to which the movable guide members are affixed in said groups, and into which said group connecting means is entered, and
  - f. means in the hollow central members for detachably affixing said connecting means to said hollow central members.
4. The combination of claim 3 further comprising
- g. connector strips entered into the hollow central members forming links between the last-named means.
5. In a cargo ship having a smooth decking,
- a. movable guide members slidably resting at their lower ends on the smooth decking,
  - b. means for holding said members in formations of separate groups
  - c. connections between said groups, and
  - d. means for adjusting the connections lengthwise to move the guide members by sliding movements on the smooth decking to shift the groups closer together or farther apart in an act of accurate adjusting the guide members of the groups into relative positions for forming knockdown hatchways.
